UNITED STATES PATENT OFFICE.

PAUL H. SCHNORMEIER, OF HUBBARD, IOWA.

ILLUMINATED-SIGN FLASHING MECHANISM.

Application filed March 18, 1927. Serial No. 176,561.

This invention relates to that class of illuminated display signs having a small number of incandescent light bulbs and a great number of reflector plates and is particularly 5 adapted to be used with the illuminated sign disclosed in my application for United States Letters Patent filed February 21, 1927, and bearing the Serial No. 169,823.

The principal object of this invention is to 10 provide a flashing effect of illuminated signs without extinguishing the electric lamps in the sign.

More specifically, the object of this invention is to provide a sign flashing mechanism 15 by passing a blind or blinds over the incandescent lamps.

A further object of this invention is to provide a sign flashing mechanism that will operate a flashing effect in any desired duration 20 of time.

A still further object is to provide a sign flashing mechanism that is easy to install and positive in its action.

A still further object is to provide a sign 25 flashing mechanism that is economical in manufacture and durable and economical in use.

These and other objects will be apparent to those skilled in the art.

30 My invention consists in the construction, arrangement and combination of the various parts of the device, whereby the objects contemplated are attained as hereinafter more fully set forth, pointed out in my claims and 35 illustrated in the accompanying drawings, in which:

Fig. 1 is a side sectional view of my invention installed in an illuminated sign.

Fig. 2 is a top plan sectional view of my 40 device mounted in an illuminated sign, taken on line 2—2 of Fig. 1 and more fully illustrates its construction.

Fig. 3 is a diagrammatical view of a different way of arranging the blinds on the endless belt and shows all of the incandescent 45 light bulbs in the sign in blinded condition.

Fig. 4 is another diagrammatical view of the same arrangement of the blinds as shown in Fig. 3 but in a position whereby the incandescent lamps are not in a blinded condition.

The illuminated signs that use a small number of incandescent lamps and a great number of reflector plates are more economical in manufacture and use than any other type of 55 sign using no reflector plates and a great number of incandescent light bulbs but their dis-

advantage to complete with other types of signs is their inability to produce a flashing effect. They are uninterruptedly illuminated and therefore do not have the attractive powers of the flash illuminated signs. I have overcome this intermittent illuminated feature as will be appreciated by those familiar with the art.

The numeral 10 designates a sign housing having the sides or faces 11 and 12. The wall 13 divides the housing into two separate compartments and thereby creates a two-faced sign. On the outside of each face may be painted letters or other characters as desired.

More specifically, the object of this invention is to provide a sign flashing mechanism 15 by passing a blind or blinds over the incandescent lamps.

A further object of this invention is to provide a sign flashing mechanism that will operate a flashing effect in any desired duration 20 of time.

A still further object is to provide a sign flashing mechanism that is easy to install and positive in its action.

A still further object is to provide a sign 25 flashing mechanism that is economical in manufacture and durable and economical in use.

These and other objects will be apparent to those skilled in the art.

30 My invention consists in the construction, arrangement and combination of the various parts of the device, whereby the objects contemplated are attained as hereinafter more fully set forth, pointed out in my claims and 35 illustrated in the accompanying drawings, in which:

Fig. 1 is a side sectional view of my invention installed in an illuminated sign.

Fig. 2 is a top plan sectional view of my 40 device mounted in an illuminated sign, taken on line 2—2 of Fig. 1 and more fully illustrates its construction.

Fig. 3 is a diagrammatical view of a different way of arranging the blinds on the endless belt and shows all of the incandescent 45 light bulbs in the sign in blinded condition.

Fig. 4 is another diagrammatical view of the same arrangement of the blinds as shown in Fig. 3 but in a position whereby the incandescent lamps are not in a blinded condition.

The illuminated signs that use a small number of incandescent lamps and a great number of reflector plates are more economical in manufacture and use than any other type of 55 sign using no reflector plates and a great number of incandescent light bulbs but their dis-

suitable means on each side of the wall 13. The downwardly extending portion of the blinds engage these guides and the blinds are thereby held in proper position to blind the lamps as they pass over them.

By the above described construction if the electric motor is running, the sprocket wheel 20 will be rotated and the blinds on the endless belt will be drawn over the various light 10 bulbs.

Any desired order or time of the flashing effect may be easily obtained by the placement in various positions of the blinds on the endless belt. In Fig. 2 the blinds are all 15 placed adjacent each other thereby first having the complete sign in unilluminated state and then spelling out one letter at a time until the complete sign is illuminated. If the blinds are placed evenly apart as shown in 20 Fig. 3 and Fig. 4 the sign will go off and on with even regularity.

The operating speed of the sign may be easily regulated by regulating the speed of the small electric motor.

25 The mechanism of my invention is very simple and can be used to advantage in signs having the maximum amount of lamps. By my construction the lamps are continuously lit during the operation of the sign and are not turned on and off as is the case with ordinary flash illuminated signs. A lamp 30 turned on and off continuously will not last as long and will take more electricity to operate it than a lamp that is uninterrupted in its illumination.

35 My invention may be easily installed in signs now on the market or it may be used as standard equipment on new signs going into use.

40 Some changes may be made in the construction and arrangement of my improved illuminated sign flashing mechanism without departing from the real spirit and purpose of my invention and it is my intention to cover by my claims any modified forms of structure or use of mechanical equivalents which

may be reasonably included within their scope.

I claim—

1. In a device of the class described, a 50 housing having openings in its side, a lamp in said housing, reflector plates in said housing for reflecting light from said lamp through said openings, an endless belt rotatably mounted in said housing, blinds secured to said endless belt and capable of passing between the lamp and reflector plates when the belt is rotated, guide members in said housing in engagement with said blinds, and a prime mover in operative engagement 55 with said belt.

2. In a device of the class described, a housing, having openings in two of its sides in the outlines of the letter or character to be displayed, a webbing in said housing, a plurality of lamps in said housing and on each side of said webbing, reflectors secured to each side of said webbing for receiving light from said lamps and diverting it through said openings, a wheel rotatably mounted adjacent each end of said webbing, an endless belt embracing said wheels and passing on each side of said webbing, blinds secured to said belt capable of passing between said lamps and reflectors on both sides of said webbing, and a means for actuating one of 70 said wheels.

3. In a device of the class described, a 75 housing having openings in one of its sides in the outlines of the letter or character to be displayed, a lamp in said housing, reflector plates in said housing for reflecting light from said lamp through said openings, an endless belt rotatably mounted in said housing, a guide wall, a member of angular form 80 secured to said belt having one of its portions capable of passing between the lamp and reflectors when the said belt is rotated and its other portion slidably engaging said guide, and a means for rotating said belt.

PAUL H. SCHNORMEIER.
